CLAIM

The ornamental design for a crossbow prod, as shown and described.

DESCRIPTION

FIG. 1 is a top perspective view of a crossbow prod, showing my new design.

FIG. 2 is a top plan view thereof.

FIG. 3 is a bottom plan view thereof.

FIG. 4 is a rear elevation view thereof.

FIG. 5 is a front elevation view thereof.

FIG. 6 is a left side elevation view thereof; and,

FIG. 7 is a right side elevation view thereof.

The dash-dot-dot broken lines in the Figures disclose unclaimed portions of the crossbow prod only, and the dash-dot broken lines disclose the boundary of the claimed design. The broken lines form no part of the claimed design.
